UNITED STATES PATENT OFFICE

138,039

DESIGN FOR A BREAD LOAF

Charton C. Frantz, Pittsburgh, Pa.

Application April 30, 1943, Serial No. 110,088

Term of patent 3½ years

(Cl. D8—1)

To all whom it may concern:

Be it known that I, Charton C. Frantz, a citizen of the United States of America, residing in the city of Pittsburgh, in the county of Allegheny and State of Pennsylvania, have invented a new, original, and ornamental Design for a Bread Loaf, of which the following is a specification, reference being had to the accompanying drawing, forming a part thereof.

In the drawing the figure is a perspective view of a bread loaf showing my new design.

The essential features of my design reside in a

bread loaf having a circular configuration, the loaf being divided transversely into a series of sections of substantially the thickness shown and longitudinally into two sections, the longitudinal division extending to but not crossing the heel sections which overlap the opposite ends of the loaf, all as shown in the drawing.

I claim:

The ornamental design for a bread loaf, as shown and described.

CHARTON C. FRANTZ.
